UNITED STATES PATENT OFFICE.

HENRY H. STRAUGHAN, OF DILLON, SOUTH CAROLINA, ASSIGNOR OF ONE-HALF TO THOMAS B. STACKHOUSE, OF SAME PLACE.

DESIGN FOR A PLOW-UPRIGHT.

SPECIFICATION forming part of Design No. 30,784, dated May 16, 1899.

Application filed April 21, 1899. Serial No. 713,974. Term of patent 7 years.

To all whom it may concern:

Be it known that I, HENRY H. STRAUGHAN, a citizen of the United States, residing at Dillon, in the county of Marion and State of South Carolina, have invented and produced a new and original Design for Plow-Uprights, of which the following is a specification, reference being had to the accompanying drawings, forming part thereof, in which—

10 Figure 1 is a perspective view of a plow-upright, showing my new design; and Fig. 2 is a side view of the same.

The leading or material feature of my design consists in the design forming the subject-matter of the accompanying illustration.

15 The upright A has the base B, from the rear end of which rises vertically the wing C, the

upper end of which is shown as terminating in a threaded tenon. The wing D rises from the front end of the base-wing B and inclines slightly to the rear to a point *d* near its upper end, where it curves forward and is shown with its front end flattened at E and having a transverse bolt-hole *e*.

Having thus described my invention, what I claim as new, and desire to secure by Letters Patent, is—

The design for a plow-upright, as herein shown and described.

HENRY H. STRAUGHAN.
